RESPIRATION APPARATUS

Alvin M. Cahan, New York, N. Y.

Application November 29, 1943, Serial No. 512,104

10 Claims. (Cl. 137—153)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to respiration apparatus adapted to deliver oxygen or other gas to a person's lungs and to effect discharge of such gas from the person's lungs to the atmosphere.

An object of the invention is to provide respiration apparatus of the type referred to which is capable of functioning as a spontaneous demand breather to supply oxygen to a person's lungs and effect discharge of gas from the person's lungs to the atmosphere in accordance with the requirements of a spontaneously breathing person, and also capable of functioning as a resuscitator to establish and/or maintain artificial respiration in a non-breathing person or in a person whose spontaneous breathing rate has declined to a dangerous point.

Another object of the invention is to provide such apparatus which will automatically function either as a demand breather or as a resuscitator, depending upon and responsive to the condition of the user's spontaneous breathing or lack of spontaneous breathing.

Another object of the invention is to provide such apparatus which will function automatically as a demand breather whenever the person using the same is breathing spontaneously at a respiration rate adequate to maintain useful consciousness and which will automatically function as a resuscitator to establish or maintain artificial respiration whenever the user's spontaneous respiration rate declines to the dangerous point.

Another object of the invention is to provide such apparatus which is capable of functioning as a demand breather and also capable of functioning as a resuscitator without the use of a negative pressure phase in the respiratory cycle.

Another object of the invention is to provide such apparatus which is capable of automatically following the respiratory rhythm of the user with absolute fidelity whenever the spontaneous respiration rate is sufficient to maintain useful consciousness and which is capable of automatically establishing or maintaining artificial respiration at a predetermined respiration rate whenever the user's spontaneous respiration rate declines to the dangerous point.

Another object of the invention is to provide such apparatus which is capable of functioning automatically to deliver oxygen or other gas to a person's lungs and to effect discharge of such gas therefrom in a regular and continuous arti-

ficial respiration cycle comprising alternate inhalation (delivery) and exhalation (discharge) phases at a predetermined minimum rate of successive occurrences of these respiratory phases, 5 whenever the user's spontaneous respiration rate does not exceed said predetermined rate, and which is capable of automatically functioning to deliver oxygen to a person's lungs and of effecting discharge therefrom in accordance with the user's spontaneous breathing requirements whenever his spontaneous respiration rate exceeds said predetermined minimum rate.

Another object of the invention is to provide such apparatus which shall be suitable for use 10 as a spontaneous demand breather for flying personnel requiring additional oxygen at high altitudes.

Another object of the invention is to provide such apparatus which shall be suitable for the 15 resuscitation of flying personnel separated from their oxygen supply through accident or enemy action.

Another object of the invention is to provide such apparatus that is not only satisfactory for 20 conventional resuscitation purposes but is also satisfactory for the treatment of patients in pulmonary edema following exposure to gaseous lung irritants such as phosgene or the like.

Another object of the invention is to provide 25 such apparatus which is capable of maintaining and/or establishing artificial respiration to thereby maintain useful consciousness at altitudes above the ceiling limit of operation of conventional demand flow oxygen systems now in use.

30 An instrument capable of performing under these varied conditions outlined in the objects above stated must be provided with delivery and expiration flow rates of oxygen or other gas delivered to and expelled from the subject using 35 the device that are automatically variable according to the particular requirements of the subject at any given time, in addition to providing for absolute control of the upper and lower limits of pressure under which the oxygen or 40 other gas is delivered to the subject. Thus, during the inspiratory cycle the instrument must be capable of delivering oxygen or other gas to the subject under positive pressure up to a predetermined pressure limit in such a manner that

45 should the subject demand an instantaneous flow of eighty-five to a hundred liters of gas per minute he shall have it without fighting for it against a negative pressure; and should the subject in the next moment demand oxygen at a rate 50 of five liters per minute, he shall have it with-

out having his lungs filled in a small fraction of the time for normal inspiration. Similarly, should the subject require exhalation at fifty liters per minute one moment, he must be permitted by the device to exhale that amount according to a definite predetermined pressure pattern; and should he, in the next moment, require exhalation to take place at two liters per minute, the device must be capable of permitting him to exhale that amount according to the same pattern, without having the pressure within the system fall off so suddenly as to condition the device for the commencement of the inhalation cycle before the subject requires it.

In addition, the device must be capable of following the respiratory rhythm of the subject with absolute fidelity so as not to impose a rhythm of its own upon him, and yet should he cease to breathe, it must furnish him intermittent positive-pressure resuscitation automatically and without change in adjustment of the apparatus, and independently of altitude.

The conventional type of resuscitator utilizes a positive-pressure phase followed by a negative-pressure phase in the respiratory cycle; that is to say the conventional type of resuscitator supplies oxygen or other gas to the person's lungs at a positive pressure and then withdraws said gas from the person's lungs by a sucking action or negative pressure phase. The most important reason for not using a negative-pressure phase at high altitude, in addition to other reasons based on physiological considerations, is that during a negative-pressure phase the partial pressure of oxygen in the rarefied atmosphere is reduced below the ambient partial pressure. The result is that the blood saturation at that altitude is reduced below the level which would prevail if the oxygen were breathed under normal circumstances.

It has been found that, by breathing oxygen under intermittent positive pressure without the interposition of a negative pressure phase, it is possible to maintain useful consciousness comfortably at altitudes approximately up to fifty thousand feet. This is not possible with the use of a conventional demand oxygen flow system since the latter operates efficiently only when using a negative phase in the cycle.

In carrying the invention into practice, a conduit is provided for communication with the tracheal passage of a person and said conduit is provided with an intake port adapted for communication with a source of supply of oxygen or other gas and said conduit is also provided with an exhaust port communicating with the atmosphere. The intake and exhaust ports are equipped with valves associated in such a manner that when one valve is open the other is closed; i. e. when the intake port is open to the source of supply to permit delivery of gas to a person's lungs, the exhaust port is closed to the atmosphere to prevent discharge of oxygen from the system, and also, when the intake port is closed to the source of supply to prevent delivery of gas to the lungs, the exhaust port is open to the atmosphere to permit discharge of the gas from the person's lungs. Pressure responsive means is provided responsive to pressure of gas in the system between the intake port and the main exhaust port to the atmosphere for controlling the operation of the main intake and exhaust valves aforesaid so that when the pressure within the system reaches a predetermined minimum level, the apparatus is conditioned for the inhalation

phase of the respiratory cycle in which the main intake port is open to the source of supply of oxygen for delivery of oxygen to the lungs of the user and the main exhaust port is closed to prevent discharge of gas from the lungs of the user and from the system to the atmosphere; and when the pressure in the system reaches a predetermined maximum level the device is conditioned for the exhalation phase of the respiratory cycle in which the main intake port is closed to the source of supply of oxygen preventing further delivery of oxygen to the lungs of the user and the main exhaust port is open to the atmosphere permitting discharge of gas from the lungs of the user and from the system to the atmosphere. Means is provided for adjusting the maximum and minimum pressure levels at which the respective delivery and exhaust means become effective.

A particular object of the invention is to provide control means for controlling the flow of gas to the user's lungs which is operative to automatically vary the rate of flow in accordance with the user's demand and operative to deliver gas to the user's lungs at pressures above atmospheric pressure.

Another particular object of the invention is to provide control means for controlling the flow of gas to the user's lungs which is operative to automatically vary the rate of flow in accordance with the user's demand and which is adjustable to preselect the pressure range within which the control means is operative to cause flow of gas to the user's lungs.

To the foregoing ends, the delivery flow control means of the invention is designed to operate responsive to variations in pressure within the user's lungs and to vary the rate of flow of gas to the user's lungs in a reciprocal relation to said pressure. Thus when the delivery means is effective, the flow of gas to the user's lungs will be controlled by the delivery control means so that the flow is greatest when the pressure within the user's lungs is at a minimum value and the flow will decrease as the pressure in the lungs rises. Means is provided for rendering the control means capable of causing flow of gas to the user's lungs when the pressures therein are above the atmospheric pressure. Means is also provided for adjusting the range of pressures at which the control means may operate to cause flow of gas to the user's lungs.

Another particular object of the invention is to provide control means for controlling the discharge flow of gas from the user's lungs to the atmosphere which is capable of affording a predetermined constant positive pressure opposing exhalation while at the same time permitting varying rates of exhalation, according to the user's requirements, and allowing the pressure within the respiratory channels to reach the ambient atmosphere pressure within a predetermined maximum period.

In accordance with the invention, discharge control means is provided for controlling the discharge of gas from the user's lungs to the atmosphere during the exhalation phase of the apparatus, said discharge control means including means for varying the rate of discharge of gas from the respiratory channels as a function of the instantaneous pressure of gas within said channels when said pressure is within predetermined limits, and means for effecting discharge of gas from the respiratory channels irrespective of said pressure limits. Provision is made for the

adjustment of the pressure limits within which the first means may operate. Provision is also made for adjusting the discharge effectiveness of the second means.

The present invention contemplates improvements in the type of apparatus disclosed in my United States Patent No. 2,288,436, dated June 30, 1942, the present invention relating primarily to the control of the delivery and discharge of gas in connection with this type of apparatus.

Other objects, advantages and features of novelty will become apparent as the invention is described in detail in connection with the accompanying drawings, in which,

Fig. 1 is a partially schematic, partially sectional view of a respiration apparatus illustrating the principles of the present invention;

Fig. 2 is a pressure flow diagram showing the pressure pattern of successive respiration cycles of said apparatus as they occur under the condition of normal respiration of a breathing person and also as they occur in artificial respiration of a nonbreathing person, said diagram also illustrating the relation between the inspiratory flow and the pressure of gas within the user's lungs.

Description of the respiration cycling instrumentalities

Now referring to the drawings for a detailed description of the invention, the respiration apparatus generally comprises delivery means for delivering oxygen or other gas to a person's tracheal passage, exhaust means for discharging gas therefrom to the atmosphere, and operating means for automatically rendering the delivery and discharge means effective alternately. The operating means includes pressure responsive means for controlling the cycling of the device to render the delivery means effective at one pressure level and to render the exhaust means effective at another pressure level. The apparatus includes delivery control means for controlling the flow of gas to the person's lungs when the delivery means is effective so that the rate of flow of gas to the person's lungs is in accordance with the person's requirements. The apparatus also includes exhaust control means for controlling the discharge of gas from a person's lungs to the atmosphere when the discharge means is effective so that the exhalation of gas from the person's lungs may be opposed by a predetermined pressure, said discharge control means being operative nevertheless to permit the person to exhale at whatever rate his condition requires, and to permit the pressure in the user's lungs to reach the ambient atmospheric pressure within a predetermined maximum period.

Referring to Fig. 1 of the drawings, the delivery means as there shown comprises a delivery conduit 1 communicating with a second conduit 2, the upper end 2a of which is adapted to lead to and communicate with any suitable inhalation mask or other means designed to introduce gas to a person's tracheal passage and thence to his lungs. The delivery conduit 1 communicates with the interior chamber 3 of a valve casing 4 provided with intake port 5 for communication with a source of supply of oxygen or other gas and adapted to admit gas to the delivery conduit 1. The exhaust means for discharging gas from the person's lungs to the atmosphere includes the conduit 2 constituting a discharge conduit communicating with the interior chamber 6 of a valve casing 7 and having an outlet communicating

with the atmosphere and comprising the exhaust port 8.

The discharge of gas by the exhaust means (when the exhaust valve 10 is open) is controlled by exhaust control means including spring loaded valve 50 and orifice or passage 51 regulated by needle valve 53. The details and operation of the exhaust control means will be more fully described later herein.

10 Thus, the delivery and exhaust means include a common conduit 1-2 communicating with the source of supply of oxygen, the user's lungs and the atmosphere.

The operating means for rendering the delivery means and the exhaust means effective alternately includes an intake valve 9 adapted for cooperation with the intake port 5, an exhaust valve 10 adapted for cooperation with the exhaust port 8, and a common actuator comprising a member 11 interconnecting the intake and exhaust valves 9 and 10 for simultaneous operation whereby when the common actuator 11 is moved in one direction the intake valve 9 is moved to a position opening the intake port 5 for admission of gas to the delivery conduit 1 and the exhaust valve 10 is moved to a position closing the exhaust port 8 to prevent discharge of gas from the discharge conduit 2, and thereby prevent discharge of gas from the lungs of the user to the atmosphere. The operating means for effecting operation of the intake and exhaust valves 9 and 10 includes pressure responsive means responsive to the pressure of gas in the common conduit 1-2 of the delivery and exhaust means, and hence responsive to the pressure of gas within the tracheal passage of the user or within the lungs of the user, for controlling the operation of the intake and exhaust valves 9 and 10. The pressure responsive means generally designated by the letter A is operative through appropriate electrical means or other suitable means to effect operation of intake and exhaust valves 9 and 10 whereby when the pressure of gas within the common conduit 1-2 reaches a predetermined pressure limit the intake valve 9 is opened and the exhaust valve 10 is closed; and when the pressure of gas within the common conduit 1-2 reaches another predetermined limit the intake valve 9 is caused to be closed and the exhaust valve is caused to be opened.

50 As shown in Figure 1, the pressure responsive means A comprises a housing 12 within which is positioned a suitable diaphragm 13 which may be made of thin metal, rubberized fabric or any other suitable material that will withstand the pressures to which it is subjected. This diaphragm 13 defines a pressure chamber 14 within the housing 12, which pressure chamber 14 is in communication through a small orifice 15 and a conduit 16 with the common conduit 1-2. The pressure chamber 14 may be placed in communication with the common conduit 1-2 at any desired point therein, but preferably the pressure chamber 14 is placed in communication with the discharge side of common conduit 1-2 as shown, and the communication is effected through the small orifice 15, so that the pressure responsive means is not so greatly affected by impulse effects of oxygen flow from the intake valve to the user's lungs. The diaphragm 13 carries an actuator comprising a stem 17 associated with the diaphragm 13 for movement therewith, said actuator stem 17 having associated therewith a contactor 18 adapted to be moved by the diaphragm 13 into and out of engagement with stationary

contacts 19 and 20 for making and breaking successively electric circuits capable of energizing and deenergizing a solenoid 21 for corresponding actuations of the intake and exhaust valves 9 and 10. A spring 22 is positioned to act against the diaphragm 13 and is designed to have such flexing characteristics that when low pressures communicated to the pressure chamber 14 are applied to the diaphragm 13, substantial movement of the latter will occur. The pressure exerted by the spring 22 upon the diaphragm 13 is adjustable by means of a screw 23 adjustably associated with the housing 12 and bearing against one end of the spring 22. The contacts 19 and 20 are associated respectively with screws 24 and 25 adjustable with respect to the housing 12 for corresponding adjustment of the contacts 19 and 20. By the means 23, 24 and 25, the pressure responsive means A is adjustable to vary the upper and lower pressure limits of gas within the conduit 1-2, at which limits the diaphragm 13 is effective to move the contactor 18 into engagement with one or the other of the contacts 19 and 20, for corresponding actuation of the intake and exhaust valves 9 and 10, to render the delivery and exhaust means effective alternately.

Movement of the common actuator 11 to operate the intake and exhaust valves 9 and 10 in one direction is effected by means of the solenoid 21, having its core 27 associated with a lever 28 pivoted as at 29 to the apparatus supporting frame 30, said lever 28 being pivoted as at 31 to the common actuator 11. Energization of the solenoid 21 serves to move the common actuator 11 to the position shown in Fig. 1 wherein the intake valve 9 is open and the exhaust valve 10 is closed. Movement of the common actuator in an opposite direction to effect closing of the intake valve and opening of the exhaust valve 10 is effected, upon deenergization of the solenoid 21, by means of the spring 32, having one end connected to the lever 28 and the other end of said spring connected as at 33 to the apparatus housing 30, the spring 32 acting upon deenergization of the solenoid 21, to move the lever 28 in a clockwise direction, referring to Fig. 1, about the pivot 29.

Operation of the respiration cycling instrumentalities

The operation of the apparatus thus far disclosed may be described as follows:

Assume that the upper end 2a of the common conduit 1-2 has been placed in communication with a person's tracheal passage and the intake port 5 placed in communication with a source of supply of oxygen or other gas, the exhaust port 8 gives access to the atmosphere, and that the adjusting means 23, 24 and 25 have been set so that the contactor 18 will make electrical contact with the stationary contact 20 when the pressure of gas within the chamber 14 is at a predetermined minimum level (e. g., at atmospheric pressure or slightly above), and so that the contactor 18 will make contact with the stationary contact 19 when the pressure in the chamber 14 reaches a predetermined maximum level. The pressure within the conduit 1-2 and the chamber 14 will at the moment of commencement of operation stand at the minimum or approximately atmospheric pressure level. At this minimum pressure level the contactor 18 will be in engagement with the stationary contact 20 completing an electrical circuit from the nega-

tive side of the battery 34 through wire 35, contacts 18 and 20, wires 36 and 37 to the solenoid 21 and thence through wire 38, relay switch 39 and wire 40 to the positive side of the battery 34, thus energizing the solenoid 21. At this point, therefore, the common actuator 11 will be in its leftward position, as shown in Figure 1, with intake valve 9 open and exhaust valve 10 closed. This position of actuator 11 causes the contact 41 carried by the lever 28 to be engaged with the stationary contact 42 completing a holding circuit from the negative side of the battery 34 through wire 43, contacts 42 and 41, wire 37 to the solenoid 21 and thence through wire 38, switch 39 and wire 40 to the positive side of the battery 34 to maintain the solenoid energized when the contactor 18 moves out of engagement with the contact 20 as the pressure in the chamber 14 rises.

Thus, at the commencement of operation of the apparatus with the pressure of gas in the conduit 1-2 and chamber 14 at a minimum level, the solenoid 21 is energized to position the common actuator 11 in its leftward position, as shown in Fig. 1, with the intake valve 9 open to admit the gas from a source of supply to the conduit 1 and the exhaust valve 10 closed to prevent discharge of gas from the conduit 2 to the atmosphere. With the valve 9 open and the exhaust valve 10 closed, gas will be delivered from the source of supply to the common conduit 1-2 and to the user's lungs, causing the pressure in the conduit 1-2 and chamber 14 to rise and acting upon the diaphragm 13 to move the contactor 18 out of engagement with the stationary contact 20 and toward a position of engagement with the stationary contact 19. During such movement of the contactor 18, the solenoid 21 will remain energized through the holding circuit above described.

When the pressure of gas within the conduit 1-2 rises to a predetermined maximum level, as determined by the adjustment of the means 23, 24, said pressure acting upon the diaphragm 13 will cause movement of the contactor 18 into engagement with the stationary contact 19, thereby completing an electrical circuit from the negative side of the battery 34 through wire 35, contacts 18 and 19, wire 45, relay 46 and wire 40 to the positive side of the battery 34. Completion of this electrical circuit will open the relay switch 39 against the action of the spring 47, thus breaking the electrical circuit through the solenoid 21 and causing the same to be deenergized whereupon the common actuator 11 will be caused to be moved in a rightward direction, having reference to Fig. 1, by the action of the spring 32 to close the intake valve 9 and open the exhaust valve 10, thus rendering the delivery means ineffective and the exhaust means effective, and thereby initiating the exhalation phase of the respiratory cycle of the apparatus during which the user of the apparatus may exhale, if he is breathing spontaneously, or, if he is not breathing spontaneously, the natural elasticity of his lungs will cause exhaust of gas therefrom which is discharged to the atmosphere through the discharge conduit 2 past the spring loaded valve 50 and also through the restricted orifice 51 to the atmosphere through the exhaust port 8.

As the gas is discharged from the conduit 2 to the atmosphere, during the exhalation phase of the respiratory cycle, the pressure within the chamber 14 decreases, causing the contactor 18 to move out of engagement with the stationary

contact 19. When the contactor 18 moves out of engagement with the stationary contact 19, the electrical circuit through the relay 46 is broken, permitting the relay switch 39 to be again closed by the action of the spring 47 to condition the circuit through the solenoid for subsequent completion to again energize the solenoid 21 at such time as the contactor 18 again comes into engagement with the stationary contact 20. The exhalation phase of the respiratory cycle of the apparatus continues until the discharge of gas from conduit 2 to the atmosphere has reduced pressure of gas in the conduit 1-2 and the chamber 14 to the predetermined minimum level, determined by the adjustment of the means 23 and 25, to cause movement of the contactor 18 again into contact with the stationary contact 20. Upon occurrence of the latter event, the solenoid 21 will again be energized as above described, causing movement of the lever 28 in a counterclockwise direction, having reference to Fig. 1, about its pivot 29 to move the common actuator 11 in a leftward direction, having reference to Fig. 1, to thereby close the exhaust valve 10, preventing further discharge of gas from the system to the atmosphere, and opening the intake valve 9 to again admit gas from the source of supply to the conduit 1, thus initiating a new inhalation phase of the respiratory cycle of the apparatus, which will continue until the pressure of gas in the conduit 1-2 and the chamber 15 rises to the predetermined maximum level, at which time the apparatus will function as above described to initiate a new exhalation phase of the respiratory cycle.

Description of delivery control means

In accordance with the invention, delivery control means, generally designated by the letter B, is provided for controlling the delivery of gas to the delivery conduit 1 and thence to the user's tracheal passage and the user's lungs in accordance with his demands or requirements. This control means is adapted to deliver gas to the conduit 1 at pressures above atmospheric pressure, and said control means is operative responsive to variations in pressure within the delivery conduit to vary the flow of gas thereto in a reciprocal relation to the pressure of gas in said conduit so that flow of gas from the source of supply to the delivery conduit 1 is greatest when the pressure of gas in said conduit 1 is at a minimum value, and the flow of gas to the conduit 1 decreases as the pressure therein rises.

Now, describing the delivery control means in detail, the same comprises a housing 60 within which is disposed a pressure responsive diaphragm 61 defining a pressure chamber 62 communicating through a port 63 and a conduit 64 with the intake port 5 of the delivery conduit 1. The pressure chamber 62 communicates with a source of oxygen or other gas through a port 65 and a conduit 66 leading to said source of supply. The port 65 is controlled by a valve 67 having a stem 68 pivotally connected to a lever 69 which is pivoted to the casing 60 and also pivoted to an actuating stem 70 fixed to the diaphragm 61. The side of the diaphragm 61 exterior to the chamber 62 is subjected to atmospheric pressure and for this purpose the apertures 71 are provided in the casing 60. Spring means adjustable relative to the casing 60 is arranged to act upon the diaphragm 61. To this end a stem 72 is fixed to the diaphragm 61 and said stem 72 has an enlarged head 72a engaged by one end of the spring 73, the

other end of which spring is engaged by an adjusting screw 74 adjustable relative to the casing 60 for varying the pressure exerted by the spring upon the diaphragm 61. A spring 75 acts between the casing 60 and the valve 67 to urge the valve 67 to closed position.

The operation of the delivery control means is as follows: Upon a decrease of pressure within the chamber 62, the diaphragm 61 will open the valve 67 to admit gas from the source of supply to the chamber 62 until the pressure of gas within the chamber 62 rises to a predetermined maximum level, as determined by the disposition of diaphragm 61 and the spring loading thereon. The flow of gas from the chamber 62 is thereby controlled responsive to the pressure of gas within the chamber 62. As the pressure of gas in the chamber 62 rises, the valve 67 gradually closes so as to gradually decrease the rate of flow of gas from the source of supply as the pressure of gas within the chamber 62 rises until at the preselected maximum pressure of gas within the chamber 62, the valve 67 is fully closed to stop the flow of gas from the source of supply. The range of pressures of gas within the chamber 62 at which the delivery control means will cause delivery of gas from the source of supply may be regulated or adjusted by the disposition of the diaphragm 61 and the preliminary loading placed thereon by the springs 73 and 75. Conveniently, the adjustment of the pressure range at which the control means is rendered effective to cause delivery of gas from the source of supply is accomplished by regulation of the pressure of the spring 73 on the diaphragm 61 by means of the adjusting screw 74. Since the pressure chamber 62 is in communication with conduit 1 when the intake valve 9 is open, the flow of gas from the source of supply to the conduit 1 is variably controlled responsive to pressure variation in conduit 1 (and hence in the user's lungs) during the inhalation phase of the respiration cycle of the apparatus. Thus, the delivery control means is operative to vary the rate of flow of gas from the source of supply to the conduit 1 in a reciprocal relation to the pressure of gas within said conduit 1, so that as the pressure in conduit 1 rises, the rate of flow decreases, and as said pressure decreases, the rate of flow increases.

For the purposes of the invention it is desirable to supply oxygen to the user of the respiration apparatus at pressures above atmospheric pressure. Where the apparatus is used for the demand supplying of oxygen to flying personnel at high altitudes or for the resuscitation of flying personnel at such altitudes, it is desirable to increase the pressure at which gas is supplied to the user as the altitude increases. Moreover, for the purposes of enabling the respiration apparatus of the invention to operate automatically as a resuscitator, it is necessary that the delivery control means for controlling the delivery of gas to the user be capable of response to a range of pressures within the user's lungs above atmospheric pressure, in order to automatically supply gas to the user's lungs during the inhalation cycle in the event that the user is not breathing spontaneously or his spontaneous respiration rate is insufficient, so that the apparatus will function automatically as a resuscitator under such conditions.

Description of exhaust control means

One of the particular objects of the invention, as above pointed out, is to provide exhaust con-

trol means for controlling the discharge of gas from the user's lungs during the exhalation phase of the respiratory cycle of the apparatus in such a manner that, whenever it is desirable, the exhalation may be opposed by a predetermined pressure, while at the same time, the user is permitted to exhale at whatever rate he requires, and in such a manner that the pressure of gas in the user's lungs is permitted to reach the ambient atmospheric pressure within a predetermined maximum period of the exhalation phase of the respiratory cycle. To this end, the exhaust control means includes means for varying the rate of discharge of gas from the discharge conduit 2 as a function of the pressure of gas in said conduit. The latter means is consequently effective to vary the rate of discharge of gas from the person's lungs as a function of the pressure of gas in the person's lungs or in his tracheal passage. Said latter means is made operative to vary the rate of discharge of gas as a function of pressure in the conduit 2 when said pressure is within predetermined limits. The exhaust control means also includes means for effecting discharge of gas from the conduit 2 irrespective of said predetermined pressure limits at which the means for varying the discharge rate is effective.

Referring specifically to Fig. 1, the discharge conduit 2 is provided with two separate outlets or channels of flow to the atmosphere which are effective to permit the discharge of gas from the conduit 2 when the exhaust valve 10 is open. One of these two outlets or channels of flow from the discharge conduit to the atmosphere is provided by the comparatively large port 52 controlled by the spring loaded valve 50. The other of said two outlets or channels of discharge flow of gas from the conduit 2 to the atmosphere is provided by the comparatively small or restricted orifice or passage 51 which is controlled by the needle valve 53.

The spring loaded valve 50 includes a valve stem 54 provided with an abutment head 55 against which one end of a spring 56 bears. The other end of said spring bears against a part of a valve adjusting member 57 threadedly associated with the valve casing 7. Rotation of the valve adjusting member 57 relative to the valve casing 7 will serve to vary the spring loading on the valve 50 and thus vary the range of pressure of gas within the discharge conduit 2, within which the valve 50 will be caused to open to permit discharge of gas from the conduit 2 through the port 52. Once the valve 50 is adjusted, it will be apparent that the same is operative to vary the effective opening of the exhaust port or outlet 52, and hence, to vary the effective discharge capacity of the exhaust means, as the pressure within the conduit 1-2, tending to open the valve 50 against the action of the spring 56, increases or decreases.

Thus, if the spring loading on the valve 50 is adjusted so that the valve 50 will open at a predetermined pressure of gas within the discharge conduit 2, it will be apparent that as the pressure of gas within the conduit 2 is increased above said predetermined pressure, the valve 50 will open to a correspondingly greater extent so that the rate of discharge of gas from the conduit 2 through the port 52 is increased as the pressure of gas within conduit 2 increases, and conversely, the rate of discharge flow of gas from the conduit 2 through the port 52 decreases as the pressure of gas within the conduit 2 decreases, until said pressure decreases to the predetermined pressure at which the valve 50 is fully closed by spring 56. It will

be apparent also that whenever the exhaust valve 10 is open and the needle valve 53 is adjusted so as to permit the passage of gas through the orifice 51, gas will continue to be discharged from the conduit 2 to the atmosphere through said orifice 51, so long as the pressure of gas within the conduit 2 is above the ambient atmospheric pressure, and irrespective of the pressure limits within which the valve 50 is operative.

10 In accordance with the invention, it is desired to regulate the discharge control means including the spring loaded valve 50 and the restricted orifice 51 in such a manner that said control means provides a predetermined pressure opposing the discharge of gas to the atmosphere during the exhalation phase of the respiratory cycle of the apparatus when the exhaust port 8 is open, while at the same time permitting the user of the apparatus to exhale at whatever rate he requires within the 15 limits of operation of the spring-loaded valve 50. It is also desired to regulate the discharge control means in such a manner that the pressure of gas within the conduit 2 will reach the ambient atmospheric pressure within a desired maximum 20 exhalation period. The maximum length of the exhalation period is regulated by adjustment of the spring loading on the valve 50 and also by adjustment of the needle valve 53, bearing in mind that the pressure drop in the common conduit 1-2 to the predetermined level, as determined by the adjustment of the pressure responsive means A, is effective to operate the intake and exhaust valves 9 and 10 to close the exhaust valve 10 and open the intake valve 9 to begin a new inhalation 25 phase of the respiratory cycle. Hence, the maximum length of the exhalation period during which the intake valve 9 is closed and the exhaust valve 10 is open to permit discharge of gas from the user's lungs to the atmosphere may be determined by adjustment of the discharge control means including the spring loaded valve 50 and the needle valve 53.

General operation of the respiration apparatus

45 As an example of the manner of operation of the respiration apparatus of the invention as a whole, including the delivery control means B and the exhaust control means comprising spring loaded valve 50 and the adjustable orifice 51, the following description of such general operation will now be given. Assuming that the apparatus is to be used at altitudes just above thirty-five thousand feet, it is desired to adjust the delivery control means so that gas will be delivered to the 50 lungs of the user at a pressure equal to eight inches of water and to adjust the exhaust control means so as to oppose exhalation or discharge of gas from the lungs of the user with an opposing pressure equal to four inches of water. The pressure limits just mentioned have been found to be suitable for proper respiration at altitudes just above thirty-five thousand feet. As the altitude increases above thirty-five thousand feet it is desirable to increase both the pressure at which gas is delivered to the lungs of the user and the pressure opposing exhalation therefrom gradually until at an altitude of approximately fifty thousand feet the apparatus would be adjusted so as to deliver gas to the user's lungs at a pressure approximately equal to twelve inches of water and so as to provide a pressure opposing exhalation equal to approximately eight inches of water. The maximum and minimum pressure limits within which the respiration apparatus will operate are of course primarily controlled by adjustment of

a pressure responsive means A. That is to say, the maximum pressure limit of the apparatus, or the pressure of gas within the conduit 1-2 which will cause operation of the intake and exhaust valves 9 and 10 to initiate the exhalation phase of the respiratory cycle of the apparatus, is determined by adjustment of the pressure responsive means A. Likewise, the minimum pressure limit of the apparatus, or the pressure of gas within the conduit 1-2, at which the intake and exhaust valves 9 and 10 will operate to initiate a new inhalation phase of the respiratory cycle of the apparatus, is also determined by the adjustment of the pressure responsive means.

For the purposes of the use of the apparatus at altitudes just above thirty-five thousand feet, the pressure responsive means A may be adjusted for a maximum pressure equal to eight inches of water. To this end, the means 23 and 24 will be adjusted so that the contactor 18 will just engage the stationary contact 19 when the pressure of gas within the conduit 1-2 is equal to a pressure of eight inches of water. Preferably, the minimum pressure limit of the apparatus will be adjusted so as to be slightly above the ambient atmospheric pressure. To this end, the means 23, 25 will be adjusted so that the contactor 18 will just make contact with the stationary contact 20 when the pressure of gas within the conduit 1-2 reaches a pressure equal to $\frac{1}{4}$ inch of water. Now the delivery control means B is preferably adjusted so as to deliver gas to the lungs of the user at a pressure slightly higher than the maximum pressure setting of the pressure responsive means A. To this end, the adjusting screw 74 of the delivery control means B will be adjusted so that the valve 67 will open whenever the pressure of gas within the chamber 62 falls below said high pressure setting of the control means B, say eight and one-half inches, say a pressure equal to eight and one-half inches of water. Now, for the particular condition of use of the apparatus with which we are dealing—namely, altitudes just above thirty-five thousand feet—the exhaust control means will be set so as to provide a constant pressure equal to a pressure of four inches of water opposing exhalation of gas from the user's lungs. To this end, the valve-adjusting means 57 and the needle valve 53 will be adjusted so that the valve 50 will just open when the pressure of gas within the conduit 2 equals a pressure of four inches of water during the exhalation phase of the respiratory cycle when the exhaust valve 10 is open. It will be understood that after the primary adjustment of a means 53, 57 has been made as just described, the needle valve 53 may be further regulated, if desired, by the user so as to permit comfortable exhalation. However, the primary adjustment will be generally satisfactory for all practical purposes. The adjustment of the various instrumentalities as just described, is merely given for the purpose of illustration of desirable adjustments for a particular condition. It will be understood that the adjustments may be varied to suit particular different conditions. Means may be provided, if desired, to automatically control the primary adjustments of the pressure responsive means A, delivery control means B and the exhaust control means as a function of altitude so that as the altitude increases, the upper pressure limit adjustments of these instrumentalities may be automatically increased.

Now, with the apparatus adjusted as above specifically described, the operation will be sub-

stantially as follows: Upon the commencement of an inhalation phase of the respiratory cycle, during which the exhaust valve 10 is closed and the intake valve 9 is open, the gas will be delivered to the lungs of the user at a pressure slightly above the maximum pressure setting of the pressure responsive means A and the gas will flow to the user's lungs at a rate determined by the rapidity of the user's spontaneous inspiration, the rate of flow gradually decreasing as the pressure within the conduit 1-2 rises until the pressure within the conduit 1-2 reaches the predetermined maximum setting of the pressure responsive means A, at which time the intake valve 9 will be closed to shut off the supply of gas to the user's lungs and the exhaust valve 10 will be opened to initiate the exhalation phase of the respiratory cycle. Upon the happening of the latter event, the gas will be discharged from the user's lungs at whatever rate he requires until the pressure within the conduit 1-2 is reduced to a pressure equal to four inches of water, at which time the spring loaded valve 50 will close and gas will continue to be discharged to the atmosphere through the restricted orifice 1 at a substantially constant rate of discharge flow until the pressure of gas within the conduit 1-2 reaches the predetermined minimum level, determined by the adjustment of the pressure responsive means A, whereupon the exhaust valve 10 will close and the intake valve 9 will again open to initiate a new inhalation phase of the respiratory cycle.

If, at any time during the inhalation phase 35 of the respiratory cycle, the user's demand for oxygen increases by a greater, or more rapid, expansion of the user's lungs, the pressure within the conduit 1-2 will, as a result, be correspondingly decreased so that the valve 67 of the 40 delivery control means will be caused to open to a greater extent to provide an increased rate of delivery of gas to the user's lungs to satisfy such increased demand.

It will be understood that the respiratory cycle 45 of the apparatus is controlled by the user's own spontaneous respiration when his spontaneous breathing rate exceeds the minimum rate (for which the apparatus is adjusted) sufficient to maintain useful consciousness. Such minimum 50 rate may, for instance, be eight respirations per minute.

When, however, the user's spontaneous respiration rate decreases below the minimum rate of eight respirations per minute, or when the user 55 ceases breathing entirely, the apparatus will automatically continue to deliver oxygen to the user's lungs and discharge gas therefrom at the rate of eight respirations per minute. This minimum rate may be adjusted in the manner later herein 60 described.

Now, referring to Figure 2, the operation of the apparatus is graphically illustrated by the pressure-flow diagram of said figure. In Fig. 1, both pressure and rate of flow are plotted against 65 time, the curve 80 representing flow during inspiration and the curve 81 representing pressure during inspiration. The curve 82 represents pressure during exhalation. At the commencement of the inhalation phase of the respiratory cycle of the apparatus of the invention, at the moment when the exhalation valve 10 is moved to closed position and the intake valve 9 is moved to open position, the pressure of gas in a conduit 1-2 is at its minimum value, as determined by the minimum setting of the pressure

responsive means A. For the purposes of this description, said minimum pressure level is represented by the zero line 83.

From Fig. 2 it will be seen that at the commencement of the inhalation phase of the respiratory cycle, the pressure of gas within the conduit 1-2 represented by the curve 81 is at minimum value and the flow of oxygen into conduit 1-2, represented by the curve 80, is greatest at such time. Thus, if the user's demand for oxygen is constant as when he is breathing spontaneously at a constant rate, or if the user's spontaneous breathing has ceased or his rate of respiration is insufficient to maintain useful consciousness, the pressure within the conduit 1-2 rises in accordance with the pressure curve 8, as the inhalation phase of the respiratory cycle progresses, and the flow of oxygen decreases in accordance with the curve 80 as the pressure within the conduit 1-2 rises until at the maximum pressure of gas within the conduit 1-2, represented at the point 84 (which is determined by the maximum pressure setting of the pressure responsive means A), the flow is at a minimum value, as represented at the point 85 on curve 80. The time period of the inhalation phase of the respiratory cycle is represented at 86 along the base line 83. The reciprocal relation between the pressure of gas in the conduit 1-2, and the flow of gas thereto during the inhalation phase of the respiratory cycle, which results from the operation of the delivery control means B, is thereby graphically illustrated. Obviously, if the user's demand for oxygen increases, during inspiration, this will be reflected by a greater or more rapid expansion of the user's lungs, resulting in corresponding variations in pressure and flow and in the time period of inspiration.

The functioning of the exhaust control means during the exhalation phase of the respiratory cycle of the apparatus is also graphically illustrated in Fig. 2. During the exhalation phase of the respiratory cycle the pressure of gas within the conduit 1-2 decreases, in accordance with the curve 82, to the pressure level represented by the point 87 within a time period E-1. The pressure level at the point 87, corresponding with the pressure at which the spring loaded valve 50 closes, is determined by the adjustment of the spring loading thereon. The exhalation period E-1 represents a normal exhalation period of a spontaneously breathing person. At the end of such normal exhalation period E-1, the normally breathing person inhales spontaneously, causing a sharp drop in the pressure of gas within the conduit 1-2, as represented by the steep decline 88 in the pressure curve, so that immediately upon the commencement of spontaneous inhalation, the pressure of gas in the conduit 1-2 drops to the predetermined minimum value at a point 89 (Fig. 2) within a very short period of time, or substantially concurrent with the commencement of inhalation. The predetermined minimum value of pressure within the conduit 1-2 occurring at the point 89 is that determined by the minimum pressure setting of the pressure responsive means A, at which time the pressure responsive means A is operative to close the exhalation valve 10 and open the intake valve 9 to commence a new inhalation phase of the respiratory cycle of the apparatus. When inhalation occurs, dropping the pressure in conduit 1-2 to the minimum value as at 89, a new inhalation cycle of the apparatus commences in which the

pressure-flow pattern of inspiration period 86 is repeated, as indicated by solid lines 80' and 81'. It will thus be seen that when the user of the apparatus is breathing spontaneously at a respiration rate more rapid than the minimum respiration rate for which the apparatus is set, his exhalation period will extend until such time as his spontaneous inhalation commences, whereupon the apparatus is immediately conditioned, as a result of the user's spontaneous inhalation, for the commencement of a new inhalation phase of the respiratory cycle of the apparatus.

Should the user's spontaneous breathing cease, or in the event that his spontaneous respiration rate does not exceed the predetermined minimum rate, the exhalation phase of the respiratory cycle of the apparatus will extend for a period E-2, at the end of which period the apparatus is automatically conditioned so that a new inhalation phase of the respiratory cycle commences irrespective of the breathing or nonbreathing of the user. (The maximum length of the exhalation period E-2 is controlled by adjustment of the exhaust control instrumentalities 53, 57.) Under such conditions, (as when the apparatus is functioning as a resuscitator), the inhalation phase of the respiratory cycle of the apparatus of the invention takes place in accordance with the diagrammatic illustration of Fig. 2 and occupies the inspiration period 86, the pressure of gas within the conduit 1-2 rising, in accordance with curve 81, to the maximum point 84 and the rate of flow decreasing, in accordance with curve 80, as the pressure rises, so that when the pressure of gas within the conduit 1-2 reaches the predetermined maximum point, the apparatus is conditioned for the exhalation phase of the respiratory cycle by the closing of the intake valve 9 and the opening of the exhaust valve 10. The exhalation phase of the respiratory cycle then takes place automatically, the natural resilience of the person's lungs tending to collapse the same. The gas is discharged from the conduit 2 through the port 52 and the small orifice 51 until the pressure of gas within the conduit 1-2 decreases to the predetermined level represented at the point 87 (Fig. 2) at which the spring loaded valve 50 closes marking the end of a period corresponding to the exhalation period E-1. Henceforth, during resuscitation, gas is discharged from the conduit 2 solely through the restricted orifice 51 during a period E-3. During this period E-3 the pressure of gas within the conduit 1-2 declines in accordance with the dotted line curve 92 until the pressure of gas within the conduit 1-2 reaches the predetermined minimum level (as determined by the minimum pressure setting of the pressure responsive means A) at a point 91 marking the end of the exhalation period E-3, at the end of which period the operation of the pressure responsive means A causes closing of the exhaust valve 10 and opening of the intake valve 9 to automatically commence a new inhalation phase of the respiratory cycle of the apparatus during which gas flows to the conduit 1-2 in accordance with dotted line pressure and flow curves 80a and 81a, in the manner above described. The curves 80a and 81a indicate a repetition of the pressure-flow pattern of inspiration period 86.

From the foregoing description, it will be apparent that the exhalation period E-2 represents the maximum exhalation period for which the apparatus is adjusted at any particular time.

The length of the exhalation period E-2 may be regulated by the adjustment of the spring-loading of the valve 50 and the adjustment of the needle valve 53. It will be apparent also that, once the apparatus is adjusted, at the end of such maximum exhalation period E-2 it automatically functions to commence a new inhalation cycle of the apparatus in which oxygen is delivered to the user's lungs whether or not he is breathing spontaneously. The exhalation phase of the apparatus extends for the full length of the maximum exhalation period E-3, of course, only in the event that the user does not spontaneously inhale prior to the end of said period E-2. Adjustment of means 50, 53 consequently controls the minimum respiration rate of the apparatus.

If the user is breathing spontaneously at a rate sufficient to maintain useful consciousness, the delivery of gas to his lungs is regulated by his demand, the rate of flow of gas varying as a reciprocal of the pressure value within the conduit 1-2. If the user ceases breathing entirely, or his respiration rate becomes insufficient to maintain useful consciousness, the apparatus nevertheless functions to initiate alternate inhalation and exhalation phases of an automatic respiration cycle so as to deliver gas to the user's lungs and discharge the same therefrom; and under such condition the flow of gas to the user's lungs varies as a reciprocal of the pressure within the conduit 1-2, and discharge of gas from the user's lungs occurs in accordance with the curves 32, 92.

It will also be apparent that the operation of the discharge control means is such that the user may exhale at whatever rate his condition requires when he is breathing spontaneously, the spring loaded valve 50 being operative to permit varying rates of discharge of gas from the conduit 1-2; and that, also, the exhalation period E-1 will extend so long as the user is exhaling, whenever his respiration rate is sufficient to maintain useful consciousness, and he may begin a new inhalation phase at any time during the exhalation period E-2 so that the length of the exhalation period E-1 is determined by, and the time within the period E-2 at which a new inhalation phase of the apparatus commences will correspond with, the time at which the user ceases exhalation and begins spontaneous inhalation. Thus, the exhaust control means of the invention makes it possible to provide a preselected positive pressure opposing exhalation while permitting the user to exhale at whatever rate his condition requires, when his spontaneous respiration rate is sufficient to maintain useful consciousness, and at the same time, the orifice 51 is continuously open during the exhalation phase of the apparatus to permit the pressure within the system to reach substantially atmospheric pressure, or the minimum pressure limit of operation of the system, within a predetermined maximum period of time E-2, to then automatically initiate a new inhalation phase of the respiratory cycle of the apparatus, in the event spontaneous respiration has ceased, or the user's spontaneous respiration rate is insufficient to maintain useful consciousness. Under the latter conditions, the apparatus functions to effect alternate delivery and discharge of oxygen to and from the user's lungs at a predetermined minimum respiration rate determined by adjustment of the apparatus. Adjustment of delivery control instru-

mentalities 61, 73, 75 controls the maximum inspiration period 86 effective when the user's spontaneous respiration rate does not exceed the predetermined minimum respiration rate. The size of the restricted orifice 51 and the adjustment of the needle valve 53 control the length of time that the exhalation period E-2 continues after the spring loaded valve 50 closes. Hence, adjustment of these latter discharge control instrumentalities controls the maximum exhalation period E-2, likewise effective when the user's spontaneous respiration does not exceed the predetermined minimum respiration rate.

It will be apparent that various types of adjustment of the pressure responsive means A, the delivery control means B, and the discharge control means 53, 57 may be made to suit various conditions, and that these adjustments may be availed of by a skilled operator or physician in a particularly advantageous manner to improve anesthesia techniques and to improve the treatment of various respiratory conditions requiring close control of the various phases of the artificial respiratory cycle.

Having thus described my invention, what I claim as new, and desire to secure by Letters Patent is:

1. In respiration apparatus of the class described, a conduit adapted for communication with gas administering means, an intake port for admitting gas to said conduit, an exhaust port communicating with said conduit and with the atmosphere, intake and exhaust valves for said intake and exhaust ports, operating means for opening and closing said valves, said operating means being operative to close the respective valves alternately and to open said valves alternately, said operating means including pressure responsive means responsive to the pressure of gas in said conduit for opening one of said valves and closing the other valve when the pressure in said conduit reaches a predetermined limit and for reversing the operations of said valves when the pressure within said conduit reaches another predetermined limit, said conduit having an outlet to the atmosphere when the exhaust valve is open, valve means including a valve for varying the rate of flow of gas through said outlet, yieldable means normally urging said last valve to a position closing said outlet, said yieldable means being arranged to act upon said last valve in opposition to the pressure of gas in said conduit acting upon said last valve and means for adjusting said yieldable means to vary the pressure range within which the pressure of gas in said conduit may effect opening of said latter valve, and a passage by-passing said last valve.
2. Respiration apparatus as claimed in claim 1, and valve means for controlling the flow of gas through said by-passage.
3. In respiration apparatus of the class described, a conduit adapted for communication with gas administering means, an intake port for admitting gas to said conduit, an exhaust port communicating with said conduit and with the atmosphere, intake and exhaust valves for said intake and exhaust ports, operating means for opening one of said valves and closing the other valve, and for reversing the operation of said valves, said conduit having two independent flow channels communicating with said exhaust port, valve means including a valve for controlling gas flow through the first channel, said last valve being arranged to open under pressure of

gas in said conduit, and yieldable means normally urging said last valve to a position closing said first channel, said yieldable means being arranged to act on said last valve in opposition to the pressure of gas in said conduit acting upon said last valve.

4. Respiration apparatus as claimed in claim 3 and valve means for controlling the flow of gas through the second channel.

5. Respiration apparatus as claimed in claim 3 wherein the effective cross-sectional area of the second channel is smaller than the effective cross-sectional area of the first channel.

6. Respiration apparatus as claimed in claim 3, wherein the effective cross-sectional area of the second channel is smaller than the effective cross-sectional area of the first channel, and manually operable valve means for controlling the flow of gas through the second channel.

7. In apparatus of the class described in combination, a conduit adapted for communication with gas administering means, said conduit having two separate discharge channels for discharging gas from said conduit to the atmosphere, valve means including a valve for controlling gas flow through the first of said channels, said valve means including a valve arranged to open under pressure of gas in said conduit, and yieldable means normally urging said valve to a position closing said first channel, said yieldable means being arranged to act upon said valve in opposition to the pressure of gas in said conduit acting upon said valve, exhaust valve means operative independently of the aforesaid valve means for controlling discharge of gas through said channels to the atmosphere, intake valve means for controlling admission of gas to said conduit, and operating means for said intake and exhaust valve means, said operating means including pressure responsive means responsive to the pressure of gas in said conduit for moving one of said intake and exhaust valve means to open position while moving the other of said intake and exhaust valve means to closed position, said intake and exhaust valve means being operative to reverse the operation of said intake and exhaust valve means.

8. In apparatus of the class described in combination, a conduit adapted for communication with gas administering means, said conduit having two separate discharge channels for discharging gas from said conduit to the atmosphere, valve means including a valve for controlling gas flow through the first of said channels, said valve means including a valve arranged to open under pressure of gas in said conduit, and yieldable means normally urging said valve to a position closing said first channel, said yieldable means being arranged to act upon said valve in opposition to the pressure of gas in said conduit acting upon said valve, exhaust valve means operative independently of the aforesaid valve means for controlling discharge of gas through said channels to the atmosphere, intake valve means for controlling admission of gas to said conduit, and operating means for said intake and exhaust valve means, said operating means including pressure responsive means responsive to the pressure of gas in said conduit for moving one of said intake and exhaust valve means to open position while moving the other of said intake and exhaust valve means to closed position, said pressure responsive means being responsive to the pressure of gas in said conduit for reversing the operation of said intake and exhaust valve means.

9. Respiration apparatus as claimed in claim 8 wherein the effective cross-sectional area of the second channel is relatively small as compared to the effective cross-sectional area of the first channel.

10. Respiration apparatus as claimed in claim 8 wherein the effective cross-sectional area of the second channel is relatively small as compared to the effective cross-sectional area of the first channel, and valve means for varying the effective cross-sectional area of said second channel.

ALVIN M. CAHAN.
